(57) **CLAIM**

The ornamental design for a hedge trimmer as shown and described.

DESCRIPTION

FIG. 1 is a right, front, top perspective view of a hedge trimmer showing our new design;

FIG. 2 is a left, rear, bottom perspective view thereof;

FIG. 3 is a right side elevational view thereof;

FIG. 4 is a left side elevational view thereof;

FIG. 5 is a front elevational view thereof;

FIG. 6 is a rear elevational view thereof;

FIG. 7 is a top plan view thereof;

FIG. 8 is a bottom plan view thereof; and,

FIG. 9 is an enlarged view of circled portion 9 in FIG. 1. The broken lines in the drawings depict portions of the hedge trimmer that form no part of the claimed design.
